(57) **CLAIM**

The ornamental design for a pre-formed concrete wall with integrated bracket, as shown and described.

DESCRIPTION

FIG. 1 is a top, front perspective view of a pre-formed concrete wall with integrated bracket in accordance with my new design;

FIG. 2 is a front elevation view thereof;

FIG. 3 is a rear elevation view thereof;

FIG. 4 is a side elevation view thereof, the other side elevation view being a mirror image thereof;

FIG. 5 is a top plan view thereof; and,

FIG. 6 is a bottom plan view thereof.

The dot-dash lines define the boundary and form no part of the claimed design.

1 Claim, 6 Drawing Sheets
